UNITED STATES PATENT OFFICE.

GEORGE E. CUSTER, OF PROVIDENCE, RHODE ISLAND.

HEATING APPARATUS.

Application filed June 1, 1923. Serial No. 642,782.

To all whom it may concern:

Be it known that I, GEORGE E. CUSTER, a citizen of the United States, residing at Providence, in the county of Providence and State of Rhode Island, have invented new and useful Improvements in Heating Apparatus, of which the following is a specification.

This invention relates to an improved heating apparatus and has for its object to provide an apparatus for use in the fire boxes of stoves, furnaces and the like, the said apparatus being capable of generating a gas from any of the available fuel oils, combining said gas with air and conducting the resulting gaseous mixture to suitable burners where the mixture is utilized as a fuel for said burners.

Another object of the invention is to provide an apparatus so constructed and arranged that the jets of flame from the various burners will be directed upon the interior walls of the heaters in which they are utilized in order that a maximum amount of heating value may be obtained from the apparatus.

Another object of the invention is to so construct the burners and generator that they may be adjusted relatively to each other to fit the various heights of fire boxes in which the apparatus may be located.

The invention consists in the combination and arrangement of parts set forth in the following specification and particularly 35 pointed out in the claims thereof.

Referring to the drawings:

Figure 1 represents a plan view of the heating apparatus embodying the invention.

Fig. 2 is a front elevation of the heating apparatus, a portion thereof being broken away to more clearly illustrate certain parts of the apparatus.

Fig. 3 is a central vertical section as taken on the line 3—3 of Fig. 1.

Fig. 4 is a central vertical section taken at right angles to the line 3—3 of Fig. 1.

Like numerals refer to like parts throughout the several views of the drawings.

In the drawings, 5 represents an annular 50 main burner consisting of two members 6 and 7 which are secured together at the front and rear by straps 8 and 9 respectively. The members 6 and 7 of the burner 5 are each provided with a chamber 10 upon the interior thereof and a portion of the outer wall is inclined at 11, and said inclined wall

is provided with a plurality of openings 12 in which burner tips 13 are located, said burner tips being provided with a plurality of small openings 14 formed therein through which the gas flows, the combustion taking place adjacent to the outer ends of said openings. The burner 5 is provided with a plurality of legs 15, each of said legs being provided with a slot 16 therein and being 60 adjustably secured to said burner through the medium of a screw 17 which passes through the slot 16.

Superimposed upon the main burner 5 is an annular auxiliary burner 18 which consists of members 19 and 20 which are secured together at the front and rear by straps 21 and 22 respectively. Each of the members 19 and 20 are provided with a chamber 23 upon the interior thereof and the upper walls of said members are provided with a plurality of openings 24 formed therein in which are located burner tips 13 similar to those previously described. The auxiliary burner 18 is adjustably secured above the main burner 5 through the medium of a plurality of supports 25, each of said supports being provided with slots 26 and 27 at the upper and lower ends respectively, the lower ends of said supports being adjustably secured to the main burner 5 through the medium of screws 28 which pass through the slots 27 while the auxiliary burner 18 is adjustably secured at the upper ends of said supports through the medium 80 of screws 29 which pass through the slots 26 in said supports.

Mounted upon the auxiliary burner 18 is a generator burner 30 which is adjustably supported beneath the auxiliary burner through 95 the medium of a pair of supports 31. The generator burner 30 is provided with a chamber 32 upon the interior thereof and in the upper wall of said burner are located a plurality of burner tips 13 also similar to those previously described. Located upon the opposite sides of the generator burner 30 are grooves 33 which extend longitudinally of said burner, and located in each of said grooves is a wick 34 preferably composed of asbestos or some other suitable material.

Mounted upon the auxiliary burner 18 and positioned directly above the generator burner 30 is a generator 35, and said generator has been separately illustrated, described and claimed in a pending application, Serial

No. 624,026, filed March 9, 1923. Briefly described, however, the generator consists of a manifold 36 which is rigidly secured to the under surface of the auxiliary burner 18. 5 The manifold 36 is provided with a chamber 37 formed therein and has a pair of generator tubes 38 mounted thereon, the interior of said tubes communicating with the chamber 37. Oil from a suitable source of 10 supply not shown is fed to the generator tubes 38 through oil supply pipes 39. Gas generated in the tubes 38 passes therefrom into the chamber 37 of the manifold 36 through a port 40 for which 15 a needle valve 41 is provided, the latter being mounted in any suitable manner in the manifold 36. Also mounted in the manifold 36 and extending parallel to the generator tubes 38 is a gas reservoir 42, the 20 interior of which communicates with the chamber 37 of the manifold 36. The opposite end of the gas reservoir 42 is secured to another manifold 43 provided with a chamber 44 with which the interior of the 25 gas reservoir communicates. A plurality of screw plugs 45 are secured in the manifold 43 and each of said screw plugs is provided with a port 46 for which needle valves 47, 48, 49, 50 and 51 are provided. The needle 30 valves 47 and 48 control the passage of gas from the manifold 43 through tubes 52 and 53 communicating with the members 6 and 7 respectively of the main burner 5. The needle valves 49 and 50 control the passage 35 of gas from the manifold 43 through tubes 54 and 55 which communicate with the members 19 and 20 respectively of the auxiliary burner 18. The needle valve 51 controls the 40 passage of gas from the manifold 43 through the tube 56 to the generator burner 30. Air passages 57 and 58 are provided in the members 6 and 7 respectively of the main burner 5, said passages communicating with the chamber 10 of each of said members and the 45 gas passing from the tubes 52 and 53 into the chamber 10 draws with it a suitable amount of air from the air passages 57 and 58. Other air passages 59 and 60 are also provided for the members 19 and 20 of the 50 auxiliary burner 18, and said passages are connected by tubes 61 and 62 respectively to the chambers 23 of the auxiliary burner 18, and a suitable amount of air is supplied with the gas passing to the chambers 23 of 55 said burner. A similar air passage 63 is also provided for the burner 30 and communicates with the chamber 32 thereof for the same purpose previously mentioned.

The general operation of the apparatus 60 is as follows:—To start the operation of the apparatus, it is first necessary to saturate the wicks 34 with a suitable inflammable material, as for example, kerosene, which is then ignited and said kerosene burns for 65 a sufficient period to pre-heat the generator

tubes 38. A suitable fuel oil fed from a suitable source or supply passes through the supply pipe 39 into the generator tubes 38 and said oil is transformed into a gas upon being subjected to the heat from the burning wicks 34. In starting the apparatus it is preferable that the valves 47, 48, 49 and 50 shall be closed in order that the first gas generated shall all pass to the generator burner. The gas generated in the generator 70 burner 30 passes from the generator tubes 38 through the ports 40 into the chamber 37 of the manifold 36, thence through the gas reservoir 42 to the chamber 44 of the manifold 43 from which it passes through the 75 tube 53 to the generator burner 30. By the time that the inflammable material upon the wicks 34 has become consumed, a sufficient amount of gas will be supplied to the generator burner 32 to thereafter provide fuel 80 for said burner and after the generator 35 has become heated to a sufficient temperature to generate the required amount of gas for the burners 5 and 18, the valves 47, 48, 49 and 50 are opened and the gas permitted 85 to flow to said burners.

It will be noted that all of the burners of the apparatus are supplied with their gaseous fuel from the generator 35 and the flow 90 of said fuel to the various members of the different burners is regulated through the medium of the needle valves 47, 48, 49, 50 and 51.

It will also be noted that the passage of 95 gas from the generator tubes 38 to the gas reservoir 42 may be regulated through the medium of the needle valves 41. The jets of flame passing through the burner tips 13 that are located in the inclined wall 11 of the main burner 5 contact with the side walls of the furnace or heater in which the apparatus is located, while the jets of flame from the burner tips provided in the upper wall of the auxiliary burner 18 contact directly with the dome portion of the heater. 100 The various burners are adjusted relatively 105 to each other and to the grate of the heater or furnace as required to fit the fire box of the heaters.

It will be understood that all of the burner tips 13 are identical in construction and are provided with a small opening 14 therein, although said openings have been omitted in the various views of the drawings in all but a few instances on account of the very 110 small size and multiplicity of said openings.

I claim:—

1. A heating apparatus comprising, in combination, a main burner, an auxiliary burner superimposed upon said main burner above the latter and adjustable vertically 115 relatively thereto, a generator burner, a generator supplying a gaseous fuel to each of said burners, said generator being heated by said generator burner and valves to con- 120 125 130

trol the flow of said fuel to each of said burners.

2. A heating apparatus comprising, in combination, a main burner, an auxiliary burner superimposed upon said main burner and adjustable vertically relatively thereto, a generator burner depending from said auxiliary burner and adjustable vertically relatively thereto, a generator supplying a gaseous fuel to each of said burners, said generator being heated by said generator burner and valves to control the flow of said fuel to each of said burners.

3. A heating apparatus comprising, in combination, an annular main burner having a sloping outer wall provided with a plurality of flame openings therein, an annular auxiliary burner adjustably mounted upon said main burner and provided with a plurality of flame openings upon the upper surface thereof, a generator burner adjustably depending from said auxiliary burner, a generator supplying a gaseous fuel to each of said burners, said generator being heated by said generator burner and valves to control the flow of said fuel to each of said burners.

4. A heating apparatus comprising, in combination, a main burner having a sloping outer wall provided with a plurality of flame openings therein, a plurality of supports adjustably mounted upon said main burner, an auxiliary burner adjustably mounted to slide vertically upon said supports and provided with a plurality of flame openings therein, a generator burner adjustably depending from said auxiliary burner, a generator supplying a gaseous fuel to each of said burners, said generator being heated by said generator burner and valves to control the flow of said fuel to each of said burners.

5. A heating apparatus comprising, in combination, a main burner embodying therein a pair of oppositely disposed semi-annular members, each of said members having a sloping outer wall provided

with a plurality of flame openings therein, a plurality of legs adjustably secured to said main burner, a plurality of supports adjustably mounted upon said main burner, an auxiliary burner adjustably mounted upon said supports and embodying therein a pair of oppositely disposed semi-annular members, each of said members having a plurality of flame openings therein, a generator burner adjustably depending from said auxiliary burner, a generator supplying a gaseous fuel to each of said burners, said generator being heated by said generator burner and valves to control the flow of said fuel to each of said burners.

6. A heating apparatus comprising, in combination, a main burner embodying therein a pair of oppositely disposed semi-annular members, each of said members having a sloping outer wall provided with a plurality of flame openings therein, a plurality of legs adjustably secured to said main burner, a plurality of supports adjustably mounted upon said main burner, an auxiliary burner adjustably mounted upon said supports and embodying therein a pair of oppositely disposed semi-annular members, each of said members having a plurality of flame openings therein, a generator burner adjustably depending from said auxiliary burner, a generator mounted upon said auxiliary burner and heated by said generator burner, means to conduct gas from said generator to each of said burners, valves to control the amount of said gas delivered to said burners and means to supply air to each of said burners.

In testimony whereof I have hereunto set my hand in presence of two subscribing witnesses.

GEORGE E. CUSTER.
